UNITED STATES PATENT OFFICE.

RANDOLPH F. HALL, OF ITHACA, NEW YORK, ASSIGNOR OF ONE-FOURTH TO THEODORE P. HALL, OF WALLINGFORD, CONNECTICUT, AND OF ONE-FOURTH TO PAUL WILSON, OF ITHACA, NEW YORK.

AIRPLANE.

Application filed November 15, 1924. Serial No. 750,104.

To all whom it may concern:

Be it known that I, RANDOLPH F. HALL, a citizen of the United States of America, and a resident of Ithaca, county of Tompkins, State of New York, have invented 5 certain new and useful Improvements in Airplanes, of which the following is a specification.

This invention relates to certain improvements in airplanes; and the nature and objects of the invention will be readily recognized and understood by those skilled in the arts involved in the light of the following explanation and detailed description of the 15 accompanying drawings illustrating what I at present consider to be the preferred embodiments of aerodynamical and mechanical expressions of the invention from among various other forms, arrangements, 20 combinations and constructions of which the invention is capable within the spirit and scope thereof.

The invention deals with the aerofoils utilized to form the lift or supporting surfaces or wings for airplanes, and aims to increase the efficiency and range of operation of such aerofoils and of the supporting surfaces or wings formed thereby, through the solution of certain problems and the reduction and substantial elimination of certain conditions encountered in use thereof which tend to decrease the efficiency of and the results obtainable with these supporting surfaces or wings in flight.

When an aerofoil is moved through the air at an angle of incidence, or when a stream of air is forced over an aerofoil disposed and maintained therein at an angle of incidence, a mass of the air is displaced 35 downwardly with the resulting creation or establishment of an upward or lift force. The lift force so developed is dependent upon the positive pressure created on the under side of the aerofoil and the negative pressure created above the aerofoil, and is attended by the establishment or creation of another force acting in a rearward direction and generally referred to as the drag force, which must be overcome in operation of the aerofoil as a lift or supporting surface.

The ratio between or the proportion of the rearward acting or drag force to the upward acting or lift force of an aerofoil determines the relative efficiency of the aero-

foil and it follows, therefor, that the greater 55 the lift force for a given or minimum drag force, the higher the efficiency of such aerofoil. The lift force of an aerofoil increases with the increase of the angle of incidence up to a certain angle known as the "critical" angle of the aerofoil, at which point the lift force falls off or decreases with an increase in the angle of incidence, so that each aerofoil has a limited range of operation 60 from low incidence to maximum high incidence or the "critical" angle of the aerofoil, the operating range, of course, varying with the particular aerofoil and the characteristics thereof.

In an airplane the supporting surface or wing forming aerofoils thereof create the desired upward or lift force by the application of power to move these supporting surfaces or wings through the air at an angle of incidence and to thus displace a 75 mass of the air, and the rearward or drag forces overcome by the power, so that the airplane is sustained and capable of flight. The flight conditions of the airplane vary 80 from the high speed and low wing incidence condition, to the low speed and high wing incidence condition. In the low wing incidence condition the maximum or high speed of the airplane is obtainable by the application of the full power which can be delivered, and the determining factor in this high speed and low wing incidence condition is the relation of the lift force to the drag force of the wing, as will be readily apparent 85 to those skilled in this art. At high wing incidence with resulting low speed of the airplane, surplus power is generally present and maximum lift force is the prime consideration and the main requirement. It follows, therefore, that a supporting surface or wing forming aerofoil in an airplane, which embodies and incorporates the characteristics of both a very high lift force 90 at high wing incidence and low speed conditions, and a high lift/drag value at low wing incidence conditions, is of high efficiency and permits of operation of the airplane to secure substantially maximum efficiency in performance.

The present invention is directed to and presents as one of its fundamental objects, the provision of supporting surface or wing forming aerofoils for airplanes which will 105

- embody and incorporate the foregoing characteristics of high lift at high wing incidence and a high lift/drag value at low wing incidence to secure a maximum efficiency in operation, as well as to increase the operating range of a wing by permitting efficient operation thereof at higher angles of incidence with resulting increase in the lift force developed, through an increase in 10 the "critical" angle of the wing.

A main characteristic of the invention resides in forming an airplane supporting surface or wing which will be capable of displacing a larger mass of air with the 15 wing under high incidence conditions and thus correspondingly create or develop a greater upward or lift force, without materially decreasing the efficiency of the wing as determined by the lift/drag ratio, under low 20 incidence and high speed conditions, and further, in which the "critical" angle of the wing is increased to permit of operation at higher incidence angles and over a greater range thereof without material decrease or 25 variation in the maximum lift force developed by the wing at such high incidence angles.

Another characteristic of the invention consists in forming an airplane supporting 30 surface or wing, of superposed aerofoils or lift surfaces disposed spaced apart at a relatively small gap/chord ratio to form an air passage therebetween through which air is displaced downwardly with the wing at 35 high angles of incidence, with resulting increase in the air mass displaced by the wing and increase in the upward or lift force thereof.

A further characteristic of the invention 40 embodies the provision of a wing or supporting surface formed of the spaced, superposed aerofoils providing the air displacement passage therebetween, in which the wing so formed is convertible by closing 45 the air displacement passage at low angles of incidence to provide a thick section wing having efficient high speed, low incidence characteristics.

Another characteristic of the invention 50 presents an airplane supporting surface or wing formed of superposed and spaced aerofoils providing an air displacement passage therebetween having vanes or flaps operable 55 to close the passage at the leading and trailing edge openings thereof and convert the wing to a thick section type having an efficient lift/drag ratio to develop a high performance at low incidence and high speed condition and to so arrange the vanes or 60 flaps at the trailing edge opening of the displacement passage that such flaps can be utilized as lateral control surfaces or ailerons.

A further characteristic of the invention 65 resides in forming longitudinally disposed slots through the upper aerofoil of a wing

embodying the spaced, superposed aerofoils, which are sloped or inclined downwardly and rearwardly to discharge into the displacement passage between the aerofoils with the object in view of causing a further displacement of air through these slots to accelerate and increase the air displacement by the wing. 70

Another characteristic and feature of the invention consists in the manner of mounting 75 the superposed aerofoils in the desired spaced relation to secure a rigid structure having the desired structural strength and aerodynamical efficiency, which mounting will be of the desired simplicity in structure 80 and arrangement.

With the foregoing general objects and characteristics, and certain other objects and results, in view, which other objects and results will be readily apparent from the following description, the invention consists in certain novel features in construction and in aerodynamical and mechanical arrangements and combinations of elements, as will 85 be more fully and particularly referred to 90 and specified hereinafter.

Referring to the accompanying drawings:

Fig. 1, is a view in end elevation, more or less diagrammatical, showing a wing of the 95 invention formed of the superposed aerofoils with the flaps for closing the passage therebetween to convert the wing to a single relatively thick section type, the flaps being disclosed in open position with the 100 closed position thereof indicated in dotted outline.

Fig. 2 is a view similar to Fig. 1 and more or less diagrammatical, showing a different arrangement of superposed aerofoils and passage closing vanes or flaps, the trailing edge portion of the wing formed by upper and lower flaps, on the superposed aerofoils, respectively. 105

Fig. 3, is a view more or less diagrammatical showing a positive stagger arrangement of the superposed aerofoils with the vanes or flaps for closing the air displacement passage, a formation of slots through the upper aerofoil being indicated by dotted 110 lines. 115

Fig. 4, is a more or less diagrammatical view in end elevation of a wing formed of three superposed aerofoils with an arrangement of vanes or flaps for closing the air 120 displacement passages therebetween to convert the wing to a thick section type.

Fig. 5, is a diagrammatical view, partly in elevation and partly in section, of a wing embodying the invention, showing the manner of structurally mounting and securing the superposed aerofoils in spaced relation to form a unit structure. 125

Fig. 6, is a diagrammatical view in elevation of a form of wing of the invention em- 130

bodying the superposed aerofoils and an arrangement of vanes or flaps for closing the displacement passage, in which a series of longitudinally downwardly and rearwardly inclined slots are formed through the upper aerofoil.

Fig. 7, is a fragmentary perspective view of the wing of Fig. 6.

Fig. 8, is a fragmentary elevation of the 10 inter-aerofoil trussing system of Fig. 5.

Fig. 9, is a more or less diagrammatical perspective view of a portion of a wing embody the invention and showing a possible mechanical arrangement of operating mechanism for the vanes or flaps.

Fig. 10, is a fragmentary detail view in elevation showing an arrangement of aileron and of a displacement closing vane or flap on a wing of the invention.

20 Fig. 11, is a more or less diagrammatical view in plan of a wing formed with a portion thereof embodying the invention, while the outer or tip portion thereof is of conventional design.

25 In the accompanying drawings several possible aero-dynamical and mechanical expressions of the various features and principles of the invention, are more or less diagrammatically disclosed purely by way of examples and not of limitation for the purpose of exemplifying and explaining the invention to enable those skilled in the art to understand the same. It will, however, be readily apparent from and after the following description and explanation, that the principles and features of the invention can be aerodynamically and mechanically expressed in various other forms and presented by other embodiments than the examples 35 illustrated and explained herewith, and the invention so contemplates and includes such other forms and embodiments involving the principles and various features of this invention.

40 A supporting surface or wing for an airplane which embodies the principles and certain features of the invention is illustrated by Fig. 1 of the accompanying drawings. In this form of the invention a pair of lift surfaces A and B are superposed in spaced relation with the leading and trailing edges of the lower aerofoil B in advance of the leading and trailing edges, respectively, of the upper aerofoil A, that is with 45 these superposed aerofoils negatively staggered. The aerofoils are suitably fixed together in spaced relation and form and provide an air displacement passage 10 therebetween normally open across and at the 50 leading and trailing edges of the aerofoils A and B. The depth of this passage 10 is such as to provide an efficient gap/cord ratio between the aerofoils A and B, as determined by the characteristics of the aerofoils, 55 so as to secure the desired air displacement

through passage 10 with the wing unit operating under high incidence and maximum lift conditions, as will be readily understood.

A vane or flap 20 of suitable section to 70 give the desired surface camber thereto, is pivotally mounted at its forward edge along the leading edge of the lower aerofoil B to swing vertically on the horizontal axis 21 to position shown in dotted outline extending upwardly across the passage 10 and rearwardly to the leading edge of the upper aerofoil to close the forward end of passage 75 10 and form a continuation of the upper aerofoil A merging into the leading edge of 80 the lower aerofoil B. The vane 20 in normal position swung downwardly to open passage 10, is shown in full lines, in which position vane 20 rests upon the upper surface of the lower aerofoil B and forms an 85 outward, forward continuation thereof. A flap or vane 30 is pivotally mounted on a horizontal axis 31 between the trailing edge portions of the upper and lower aerofoils 90 A and B, and this vane 30 is mounted with the axis 31 extending therethrough intermediate the forward and rear edges thereof, so that the vane is rotatable or capable of oscillation thereon to swing the rear edge portion upwardly and the forward edge portion 95 downwardly to the position shown in dotted outline with the vane extending across and closing passage 10 between the trailing edges of aerofoils A and B in upward and rearward continuation of the 100 lower aerofoil B. In open position, shown in full lines in Fig. 1, the rear vane or flap 30 is swung to position intermediate and spaced from the upper and lower aerofoils 105 A and B, respectively, to open the trailing end of passage 10.

The design and arrangement of the upper and lower aerofoils A and B, and the forward and rear vanes 20 and 30, is such that 110 with the forward and rear vanes swung to position closing passage 10, the wing unit is converted to a single relatively thick section type of wing having such a section and characteristics as to develop an efficient lift/drag value at low incidence and high 115 speed conditions. In flight operation under high incidence and low speed conditions where maximum lift is desired, the forward and rear vanes are swung to open position 120 which opens the passage 10 and results in a displacement of air downwardly and rearwardly therethrough. This displacement of air through passage 10 is in addition to and augments the normal displacement by aerofoils A and B, and increases the total mass 125 displaced with a resulting increase in the upward or lift force developed by the wing at high incidence. Further, the range of high incidence angles of the wing is extended, that is, the "critical" angle for the 130

wing is increased so that it may be operated at higher angles of incidence and the lift force created remains substantially constant without material decrease over the range 5 of high incidence angles made possible. In the foregoing manner the efficiency and performance of an airplane equipped with wing units embodying the foregoing principles is materially increased, as the speed range 10 is increased as well as the weight which may be carried, so that a more efficient loading is possible and a slower landing speed secured without material decrease in the efficiency at low incidence and high speed. Likewise 15 the possible flying speed is decreased to permit of slow speed without danger of "stalling" or loss of flying speed and control of the airplane.

A wing embodying the invention is disclosed in Fig. 2 as presenting another form and arrangement of aerofoils and vanes or flaps. In this form of the invention aerofoils A' and B' of suitable section are superposed in spaced relation to form the air displacement passage 10, and the upper aerofoil A' is provided with a trailing edge flat 30' in rearward continuation thereof and pivotally mounted thereon along the horizontal axis 31'. The lower aerofoil B is provided with a similar trailing edge flap 32 in rearward continuation thereof pivotally mounted thereon along the horizontal axis 33. The leading edge portion or forward section of the lower aerofoil B is 25 pivotally mounted along the horizontal axis 21' and forms the forwardly extending flap 20' terminating at the leading edge of the upper aerofoil A. In normal closed position to convert the wing unit to a single 30 relatively thick section wing, the rear flaps 30' and 32, are in position converged with their trailing edges engaged to close the rear end of passage 10, and the forward flap 20' of lower aerofoil B is in position engaging 35 the leading edge of aerofoil A to close the forward end of passage 10, as shown in full lines in Fig. 2. The passage 10 is opened with the wing unit at high incidence to permit displacement of air therethrough, as hereinbefore explained, by swinging forward flap 20' downwardly, and swinging the rear flaps 30' and 32 to disengaged, diverged and open position. The displacement passage opening position of the flaps 20', 30' and 32 are indicated by dotted lines in Fig. 2. It will here be noted that the rear flaps 30' and 32 are of the aileron type and the invention contemplates and includes the use of either or both of these flaps as lateral control surfaces or ailerons for such a wing in an airplane, the operation of which can conform to conventional practice well understood in this art.

In the form and embodiment of the invention presented in Fig. 3, the superposed,

spaced aerofoils A'' and B'' are arranged with the leading edge portion of the upper aerofoil A'' extended forwardly beyond the lower aerofoil B'', and a vane 20'' is pivotally mounted on a horizontal axis 21'' along 70 the under surface of upper aerofoil A'' adjacent the leading edge thereof. This vane 20'' is swingable downwardly, as shown in dotted lines, to position across and closing passage 10 and forming a substantial upward and forward continuation of B'' to the leading edge of upper aerofoil A''. In position opening passage 10, the vane 20'' is swung upwardly against the under side of aerofoil A'', as shown in full lines. A trailing edge flap 32, similar to that of Fig. 2, is pivotally mounted on lower aerofoil B'' for swinging movement upwardly to position across and closing the rear end of passage 10 and forming an upward continuation of aerofoil B'', to the trailing edge of aerofoil A'', as shown by dotted lines. The open, high incidence position of vane 20'' and flap 32 to open air displacement passage 10, is shown in full lines. 85 90

The invention presents another feature in the provision of slots through the upper aerofoils to aid in the air displacement through passage 10, and one possible arrangement of such slots is indicated by dotted lines in Fig. 3, and further referred to in connection with the disclosures of Figs. 6 and 7, hereinafter. In Fig. 3 the upper aerofoil A'' is formed with the longitudinal slot 40 extending upwardly and rearwardly 100 through the forward portion thereof to the rear of vane 20'', and the longitudinal slot 41 spaced rearwardly from slot 40 and extending upwardly and forwardly through the aerofoil. These slots 40 and 41 both communicate with the displacement passage 10, and at their outer ends open to and communicate with the atmosphere.

In Fig. 4 of the accompanying drawings the invention is presented in a wing formed of the series of spaced superposed aerofoils or lift surfaces A, B, and C, arranged in negatively staggered relation and providing the air displacement passages 10 and 10' therebetween, respectively. A vane 22 is pivotally mounted on the horizontal axis 23 intermediate the leading edges of the upper and intermediate aerofoils A and B, respectively, and a similar vane 22 is pivotally mounted on a horizontal axis 23' intermediate the leading edges of the intermediate and lower aerofoils B and C, respectively. The vanes 22 are swingable to the full line positions extending across and closing the leading or forward ends of the displacement passages 10 and 10', respectively, and likewise connecting and extending between the leading edges of aerofoils A, B and C, to form a surface in continuation of the upper surface of aerofoil A extending downwardly 110 115 120 125 130

and forwardly to the leading edge of aerofoil B. These vanes 22 are further swingable to the dotted line positions disposed intermediate the aerofoils A, B and C, respectively, to open the forward ends of the air displacement passages 10 and 10' between the aerofoils. Vanes 30 are pivotally mounted on horizontal axis 31 intermediate the trailing edges of the upper and intermediate aerofoils A and B, and the trailing edges of the intermediate and lower aerofoils B and C, respectively, and these vanes 30 are swingable to close the rear or trailing ends of passages 10 and 10', respectively, with the vanes extending between the trailing edges of aerofoils A, B and C, and forming an upward and rearward continuation of the lower surface of aerofoil C, to the trailing edge of aerofoil A, as shown in full lines by Fig. 4. The position of vanes 30 to open passages 10 and 10', respectively, between aerofoils A, B and C, is indicated in dotted outline. Thus, the wing of Fig. 4, is operable at high incidence condition with vanes 22 and 30 swung to position opening passages 10 and 10' to permit displacement of air therethrough to increase the lift force of the wing unit, as hereinbefore explained, while at low incidence the vanes 22 and 30 are swung to close passages 10 and 10', and convert the wing unit into a single thick section type wing.

Another possible form and arrangement of vanes for closing the forward or leading end of the air displacement passage 10 between superposed aerofoils A² and B² embodying a wing of the invention is disclosed in Fig. 5. In this form of the invention the aerofoils A² and B² are superposed to provide the displacement passage 10 therebetween and the rear or trailing end of the passage is adapted to be opened and closed by the pivotally mounted vane 30 swingable on the horizontal axis 31 intermediate the trailing edges of the aerofoils, in a manner hereinbefore described and explained. Complementary upper and lower vanes 24 and 24' are mounted on a horizontal axis 25 disposed forward or in advance of the leading edges of the upper and lower aerofoils A² and B², and swingable away from each other or upwardly and downwardly respectively, to the dotted line position extending across and closing the forward or leading end of passage 10, with the upper vane 24 forming a forward and downward continuation of aerofoil A² and the lower vane 24' forming a forward and upward continuation of aerofoil B². Thus, in passage closing position (dotted lines) of the forward vanes 24 and 24' and the rear vane 30, the passage 10 between aerofoils A² and B² is closed, and a single thick section type wing is formed for low incidence conditions, while in passage open-

ing position (full lines) of these vanes the high lift, high incidence wing involving the principles of the invention is presented.

A further feature of the invention applicable to the various forms of wings disclosed and described herein, is illustrated in Fig. 5, in connection with Fig. 8, and embodies a structural arrangement for mounting and securing the superposed aerofoils in the required spaced, air displacement passage providing relation to form the wing of the invention. The upper and lower aerofoils A² and B², referring to Fig. 5, are formed with usual front and rear wing spars or girders F and R, respectively, or any equivalent structure, which are in substantial vertical alignment with the aerofoils in proper superposed relation. According to this feature of the invention suitable bracing or trussing T is interposed between each pair of superposed front and rear spars F and R, respectively, of the superposed aerofoils A² and B², which trussing rigidly secures and maintains the aerofoils in the desired superposed spaced relation, and forms a rigid wing unit of the required structural strength and with a minimum of weight and parasite resistance within passage 10. It will be evident that this feature of the invention can be readily expressed in other ways to meet the requirements of each particular installation, without going beyond the broad principle of the invention, and further that such arrangements are applicable to the various forms of the wing of the invention disclosed, as well as other forms embodying the invention.

In Figs. 6 and 7 of the drawings a wing of the invention is disclosed consisting of upper aerofoil A³ and lower aerofoil B³ disposed in spaced superposed relation and having a forward passage closing vane 20 and a rear passage closing vane 34. In this instance forward vane 20 is pivotally mounted on axis 21 along the leading edge of lower aerofoil B³ and rear vane 34 is pivotally mounted on axis 35 along the trailing edge of lower aerofoil B³. The operation of these vanes will be clear from the foregoing descriptions and are swingable to open passage 10 for high incidence conditions, or to close passage 10 and convert the wing unit into a single thick section type for low incidence conditions. The upper aerofoil A³ is formed with the substantially parallel, spaced slots 50 extending thereacross and longitudinally thereof intermediate the leading and trailing edges of the aerofoil. These slots 50 open through the upper surface of aerofoil A³ and extend downwardly therethrough at a rearward inclination, to and discharging into the air displacement passage 10 between the aerofoils A³ and B³. In operation of the form of wings of Figs. 6 and 7, with the wing at high incidence and passage 10 open,

air is displaced through this passage, as explained, and is likewise drawn through slots 50 in the upper aerofoil to assist in increasing the air displaced by the wing under high incidence and high lift conditions. The invention is, of course, not limited to the number of slots or their exact shape and form as disclosed in the example of this feature of the invention presented by Figs. 6 and 7.

10 A possible form of operating mechanism for the forward and rear vanes for opening and closing the air displacement passage of a wing of the invention, is more or less diagrammatically illustrated in Fig. 9 of the accompanying drawings. A wing formed of the superposed aerofoils A and B having the displacement passage 10 therebetween, and the forward vane 22 and rear vane 32 pivotally mounted on the axis forming shafts 23 and 33, respectively, is shown, in which the shaft 23 for the forward vane 22 is pivotally mounted intermediate the leading edges of the aerofoils on bearings 26 suspended and supported from the aerofoils by suitable hangers or the like 27, while the rear vane or flap 32 is pivotally mounted by shaft 33 along the trailing edge of the lower aerofoil B³. The shafts 23 and 33 are extended at one end of the wing 30 and shaft 23 is provided with a bell crank 60 fixed thereon, while shaft 33 has an arm 64 mounted and fixed thereon. A rod or tube 63 connects arm or crank 64 on shaft 33 with one arm of the bell crank 60 on shaft 23. At any desired position, preferably accessible to the pilot of an airplane of which the wing forms a part, a hand operating lever 62 is mounted on a shaft 65 and is provided with an arm 66 operatively connected with the bellcrank 60 on shaft 23, by the rod or link 61. Thus, by operating lever 62, the shafts 23 and 33 are simultaneously rocked or rotated to swing the vanes 22 and 32 to passage opening position, or to passage closing position, as will be clear by reference to Fig. 9 of the drawings. If desired or found expedient, the front and rear vanes can be separately and independently operated by suitable mechanism and it is not intended by the illustrated example to limit the invention to simultaneous operation of these vanes. The mechanism illustrated is merely for the purpose of an example to show a possible manner of operating the vanes, and it will be obvious that various other arrangements and mechanical expressions for operating the vanes may be employed to fulfill the conditions presented by the type, form and arrangement of the vanes or flaps utilized.

15 The rear vanes or flaps of the wings of the invention can be utilized to provide and form the lateral control surfaces or ailerons for the wing on which mounted, and can be operated and controlled by the usual or

any other desired mechanism for this purpose. Referring particularly to Figs. 2 and 3 of the drawings, for example, the rear vanes or flaps of the wings shown are capable of operation as lateral control surfaces 70 or ailerons, and the invention contemplates and includes such use and operation as a feature thereof. In Fig. 10, the formation of a wing of the invention with a separate aileron is disclosed. The wing embodies 75 superposed aerofoils A'' and B'' having the rear flap 32 for opening and closing the rear or trailing end of displacement passage 10, and an aileron or lateral control surface 36 is pivotally mounted along the trailing edge of aerofoil A'' in substantial continuation thereof, and operable in the usual or any desired manner familiar in this art.

80 A form of wing W, is disclosed in Fig. 11 of the drawings, embodying the spaced, 85 superposed aerofoils A and B to form passage 10 therebetween, and having the passage closing vanes 22 and 32, all arranged and mounted in accordance with the principles of the invention, in which the outer 90 end or top portion O of the wing is formed of conventional design having a section substantially conforming to the section of wing W when converted by vanes 22 and 32 to the single thick section wing for low incidence—high speed conditions, or to one of the superimposed sections. The conventional tip portion O of the wing is provided with the usual or other aileron or lateral control 95 surface 37. Thus, an airplane wing or supporting surface can be formed having a part or section thereof formed to embody the principles of the invention hereof, and the remaining part or section thereof formed in accordance with the conventional or other 100 types of wings.

105 By the invention, an airplane supporting surface or wing is provided in which high efficiency is obtained through an increase in the lift developed at high angles of incidence and an increase in the range of high incidence angles is secured without material decrease or variation in the lift over the range of high incidence, while retaining in the wing the desired characteristic of high lift/drag value at low incidence, through the convertible features of the invention. In this manner, an airplane equipped with wings of the invention can be more efficiently loaded and its range of operation materially increased, including an increase in the speed range of the airplane with a minimum low flying speed.

110 In those forms of the invention including slots or openings in the aerofoils, any suitable means may be employed, such as shutters, vanes or the like, for opening and closing such slots or openings if found expedient or desirable, and such means may 115 take the form of the vanes or flaps dis- 120 125

closed for opening or closing the wing air displacement passages. Further, attention is directed to the fact that any suitable number or arrangement of aerofoils or lift surfaces may be employed to form a wing embodying and presenting the broad principles of the invention, and it is not intended to restrict the invention to the number of aerofoils disclosed in the illustrated examples.

In the appended claims the term "airplane wing" is employed in a broad, generic sense to include any and all lift surfaces or aerodynamic elements, symmetrical or non-symmetrical in the base section, having or embodying the general characteristics of lift through reaction of air thereon.

It is also evident that various other changes, variations, modifications and substitutions might be resorted to without departing from the spirit and scope of my invention, and hence I do not desire to limit myself to the exact and specific disclosures hereof.

Desiring to protect my invention in the broadest manner legally possible, what I claim is:

1. An airplane wing embodying superposed aerofoils spaced apart to form an air displacement passage therebetween, and means for opening and closing said passage.

2. An airplane wing embodying superposed aerofoils spaced apart to form an air displacement passage therebetween, and means for opening and closing the forward and rear ends of said passage.

3. An airplane wing having an air displacement passage extending therethrough from leading to trailing edge thereof, and means for closing said passage to convert said wing into a substantially unbroken surfaced wing.

4. An airplane wing embodying superposed aerofoils spaced apart to provide an air displacement passage therebetween, and means for closing said passage to convert the aerofoils to form a single wing section.

5. An airplane wing embodying superposed aerofoils spaced apart to provide an air displacement passage therebetween, and means for connecting the leading edges of said aerofoils and closing the forward end of said passage.

6. An airplane wing embodying superposed aerofoils spaced to provide an air displacement passage therebetween, means for connecting the leading edges of said aerofoils and closing the forward end of said passage, and means for connecting the trailing edges of said aerofoils and closing the rear end of said passage.

7. An airplane wing embodying superposed aerofoils spaced to provide an air displacement passage therebetween, means operable to extend between and join the

leading edges of said aerofoils to close the forward end of said passage, means operable to extend between and connect the trailing edges of said aerofoils to close the rear end of said passage, the said means in passage closing positions converting said aerofoils to a single wing.

8. An airplane embodying superposed aerofoils spaced to provide an air passage therebetween, and vanes operable to close said passage.

9. An airplane wing embodying superposed spaced aerofoils providing an air displacement passage therebetween, and pivoted members operable to close said passage.

10. An airplane wing embodying superposed aerofoils spaced to provide an air displacement passage therebetween, a member pivotally mounted at the forward end of said passage, a member pivotally mounted at the rear end of said passage, and the said members operable to open and close said passage.

11. In an airplane wing, superposed aerofoils spaced to provide an air displacement passage therebetween, and members operable to close the forward and rear ends of said passage and convert said spaced aerofoils into a single wing section.

12. In an airplane wing, superposed aerofoils spaced to provide an air displacement passage therebetween, members operable to close the forward and rear ends of said passage, said members in passage closing position converting said spaced aerofoils into a single wing section, and means for operating said members.

13. In an airplane wing, superposed aerofoils spaced to provide an air displacement passage therebetween, members operable to close the forward and rear ends of said passage and convert said spaced aerofoils into a single wing section, and means for simultaneously operating said members.

14. An airplane wing embodying spaced aerofoil sections in fixed relation, and means for converting said spaced sections into a single aerofoil section.

15. An airplane wing embodying spaced upper and lower aerofoil sections in fixed relation, and means for converting said spaced sections into a single aerofoil section.

16. An airplane wing embodying superposed aerofoils spaced to provide an air displacement passage therebetween, members for closing said passage, and certain of said members operable as lateral control elements for said wing.

17. An airplane wing embodying superposed aerofoils spaced to provide an air displacement passage therebetween, members at the forward and rear ends of said passage for opening and closing the same, and said rear members operable as the lateral control elements for said wing.

18. An airplane wing embodying superposed aerofoils spaced to provide an air displacement passage therebetween, a member at the forward end of said passage and a member at the rear end of said passage, said members operable to open and to close the said passage, and said rear member forming a lateral control element for the wing.
19. An airplane wing embodying superposed spaced aerofoils, and the upper aerofoil formed with a series of longitudinally disposed, substantially parallel slots extending therethrough and inclined downwardly and rearwardly.
20. An airplane wing embodying superposed spaced aerofoils providing an air displacement passage therebetween, the upper aerofoil formed with slots extending therethrough in communication with said displacement passage, and means for opening and for closing said air displacement passage.
21. An airplane wing embodying superposed, spaced aerofoils providing an air displacement passage therebetween, the upper aerofoil formed with air passages extending therethrough in communication with said displacement passage, and means for closing said air displacement passage at the forward and rear ends thereof to convert said aerofoils to a single wing section.
22. An airplane supporting surface or wing embodying superposed and spaced aerofoils having a relatively small gap/chord ratio, trusses rigidly connecting and securing said aerofoils in superposed relation, and means for converting said aerofoils to form a single wing section.
23. An airplane supporting surface or wing embodying superposed and spaced aerofoils having a relatively small gap/chord ratio, each of said aerofoils including a front and rear wing spar, trusses rigidly connecting the front spars and the rear spars, respectively, of said aerofoils to secure the same in fixed superposed wing forming relation, and means for converting said aerofoils to form a single wing section.
24. An airplane wing embodying spaced superposed aerofoils in fixed relation having a relatively small gap/chord ratio, and means for converting said aerofoils to form a single wing section.
25. An airplane wing embodying superposed aerofoils fixed in spaced relation to have a relatively small gap/chord ratio, and means for converting said aerofoils to form a single wing section.
26. An airplane wing formed with an air displacement passage extending therethrough from leading to trailing edge thereof to cause displacement of air downwardly with the wing at high incidence angles, and means for closing said passage with the wing at low incidence angles.
27. An airplane wing formed of superposed aerofoils spaced to provide an air displacement passage therebetween to displace air downwardly therethrough with the wing at high angles of incidence, and means for closing said passage to present the wing as a single relatively thick section at low angles of incidence.
28. An airplane wing formed of superposed aerofoils spaced apart and having a relatively small gap/chord ratio, the said aerofoils providing an air displacement passage therebetween to cause displacement of air downwardly therethrough with the wing at high angles of incidence, and means for closing the leading and trailing ends of said passage to present the wing as a single relatively thick section at low angles of incidence.
29. An airplane wing embodying aerofoils spaced apart to form an air displacement passage therebetween, lateral control elements for said wing, and means for closing said passage to convert said aerofoils to form a single wing section.
30. An airplane wing embodying aerofoils spaced apart to form an air displacement passage therebetween, lateral control elements for said wing, and members operable to open and close said air displacement passage.
31. An airplane wing embodying aerofoils spaced apart to form an air displacement passage therebetween, an aileron on one of said aerofoils, and members operable independently of said aileron to close said passage and convert the aerofoils to form a single wing section.
32. An airplane wing embodying a series of aerofoils spaced apart to form air displacement passages therebetween, and members for closing the air displacement passages to convert said aerofoils to form a single wing section.

Signed at Ithaca, New York, this 6th day of November, 1924.

RANDOLPH F. HALL.
